UNITED STATES PATENT OFFICE.

MORRIS NEWGOLD, OF NEW YORK, N. Y.

AIRSHIP.

1,178,174.

Specification of Letters Patent.

Patented Apr. 4, 1916.

Application filed December 29, 1911. Serial No. 668,446.

To all whom it may concern:

Be it known that I, MORRIS NEWGOLD, a citizen of the United States, and a resident of the borough of Manhattan, city, county, and State of New York, have invented certain new and useful Improvements in Airships, of which the following is a specification.

My invention relates to air ships of the kind commonly known as aeroplanes or heavier than air machines and has for its object to construct such air ships so that the operator's car and consequently the operator and any part of the mechanism carried by said car will always remain in equilibrium regardless of any transverse tilting of the remainder of the machine or ship.

A further object of my improvement is to provide said ship with devices in the nature of ailerons which come into operation as the ship is transversely tilted and operate to return it to a normal or level position.

My invention will be fully described hereinafter and the features of novelty will be pointed out in the appended claims.

Reference is to be had to the accompanying drawings in which—

Figure 1 is a front elevation of my improved air ship; Fig. 2 is a cross-section thereof in diagrammatic form showing the planes tilted; Fig. 3 is a plan view of the said ship; Fig. 4 is a side elevation thereof; Fig. 5 is a partial longitudinal section of the ship on an enlarged scale; Fig. 6 is an enlarged partial longitudinal section on the line 6—6 of Fig. 3 and Fig. 7 is a similar view of a different form of my invention.

In the drawings the main frame of the air ship is composed of a number of spaced bars A extending from front to rear and having their forward portions secured to rings B and B' formed of angle iron or any suitable material as shown best in Fig. 5. The rear ends of said bars A are secured to a bracing ring C, similar rings C' being fastened to said bars A at intervals intermediate of the rings B' and C the whole construction providing a substantially rigid frame preferably tapering from a point slightly behind the ring B' to the rear ring C. The usual vertical rudder D for guiding the vessel to the right or left is mounted on a rod D' journaled in bearings E located on the main frame at the rear end thereof. The customary arms D² are fixed on said rod D' so as to preferably extend at substantially right angles to the axis thereof and serve as a means

to which the one end of each of the customary steering wires or ropes F are secured. The steering wires F extend to the front of the vessel and pass over pulleys F' journaled in bearings F² located on a platform G secured to the rings B and B' at a distance below the axis thereof. After passing over the pulleys F' the said steering wires F extend to a drum H so as to be wound on and unwound therefrom as a hand wheel H' connected with said drum H is rotated in one direction or the other and thus serving to swing the rudder D in a horizontal plane and guide the vessel to the right or left as desired. The drum H is journaled in a standard I secured to and extending upwardly from the platform G, said standard I also serving as a journal for a second drum J to which a hand wheel J' is secured. Wires or ropes K extend from this drum J over suitable pulleys K' located on the platform G and each have their one end secured to an arm L, which arms L extend in opposite directions from a horizontal shaft L'. This horizontal shaft L' is journaled in bearings L² supported on the main frame and carries the horizontal rudders L³ which are swung in a vertical plane as the hand wheel J' is actuated and serve to cause the vessel to rise or fall according to the direction in which said rudders extend relatively to the horizontal. An operator's seat M is located in close proximity to the hand wheels H' and J' and has its front edge supported on uprights M' extending upwardly from and secured to the platform G and its rear edge supported on a brace M² extending and fastened to one of the bars A as clearly shown in Fig. 5. The platform G further serves as a support for the operating engine N, the driving shaft N' of which carries a sprocket wheel N² connected by means of a sprocket chain N³ with a second sprocket wheel O. The said sprocket wheel O is fixed on a propeller shaft O' which also carries the propeller O² and is journaled in cross bars O³ secured to the rings B and B'. These rings B and B' are provided on the outer peripheries of their horizontal flanges with bearing rollers P journaled in bearings P' secured at intervals to said rings B and B'. The said rollers P are adapted to travel on the inner surface of the horizontal flanges of rings Q and Q' also preferably made of angle iron or other suitable material and arranged in opposed relation to the rings B and B' as illustrated in Fig. 5, and connect-

ed by means of connecting bars Q^2 to maintain said rings in proper spaced relation to each other.

A preferably continuous bar R is secured to the upper portion of the ring Q and extends in opposite directions from the axis thereof, a similar bar R' being similarly secured to the ring Q'. This bar R' extends in the same general direction as the bar R but is curved so as to be located in a somewhat lower plane than said bar R. Cross-bars R² extend at intervals from the bar R to the bar R' and serve to connect these bars in such a manner as to form supporting frames located on opposite sides of the rings Q and Q' as is clearly shown in Figs. 1 and 3. As will be seen by referring to the said figures these cross-bars R² project beyond the bars R and R' and have their free ends connected through the medium of rods R³ which thus also form parts of the supporting frames above referred to. The said frames are covered with any suitable fabric to form aeroplanes S which in the specific illustration are located at each side of the vessel in a manner to provide a type of aeroplane commonly known as a monoplane. In order to brace the aeroplane frames and provide the necessary rigidity braces T extend from the bars R and R' to rods T' which in turn are carried by the lower portions of the rings Q and Q', said braces T being further secured to the said rings at T² if desired. The one rod T' preferably extends beyond the ring Q as shown in Fig. 1 and has its free ends secured to upwardly extending braces T³ spaced from each other and arranged in pairs at each side of the vessel with their upper ends fastened to the bar R. A pivot pin U extends between the lower free ends of each pair of braces T³ and serves as a pivot for one arm U' of angle members arranged in pairs and carrying traction wheels U² journaled at U³ as shown best in Fig. 4. The other arm U⁴ of each angle member is pivotally connected at U⁵ with a rod U⁶ the opposite end of which is pivotally connected with a slide U⁷, each slide being arranged to travel between a pair of said braces T³. Coil springs U⁸ each have their one end connected with one of said slides U⁷ and their other end secured to a pin U⁹ located between each pair of braces T³. The traction wheels U² are thus resiliently mounted, the springs U⁸ serving to take up the shock due to contact with the ground or other landing surface as the vessel alights. A single rear wheel V is journaled between the free ends of a pair of bars V' which are secured to the rings Q and Q' and are made of a material which preferably has a certain amount of elasticity so that this wheel V is also resiliently mounted and thus aids the wheels U² to take up any shocks. The wheels U²

and V form a traction means on which said vessel may be shifted from place to place.

Spring actuated rollers W similar to ordinary shade rollers are journaled in bearings W' located at the outer ends of the 70 aeroplane frames composed of the bars R, R', R² and rods R³ and carry curtains or ailerons W² made of any suitable fabric or other material. In the form of my invention illustrated in Figs. 1 to 6 inclusive triangular frames X each having their apices connected by a cross rod X' are secured to the aeroplane frames so as to extend downwardly and rearwardly therefrom in close proximity to said bearings W' and rollers W for the purpose to be more fully described hereinafter. Each aileron W² has its free edge provided with an eyelet W³ to which the one end of wires or cords Y, Y' are secured, which wires each pass over a roller 85 X² journaled on the bars X' and over rollers X³ journaled on each aeroplane frame and have the other ends fastened at X⁴ to a wire or cord Z as illustrated in Figs. 1 and 2. This wire Z has its opposite ends secured to a drum Z' connected with a band wheel Z² and also journaled in the standard I, said wire Z extending in opposite directions from said drum and passing over pulleys Z³ carried by the platform G. After passing 95 from the pulleys Z³ the wire Z passes over pulleys Z⁴ journaled at the outer ends of the aeroplane frames and then over additional pulleys Z⁵ rotatably secured to two of said bars Q² which extend from the ring 100 Q to the ring Q'. The said wire Z thus forms a substantially continuous loop extending transversely of the vessel as shown best in Fig. 2 and is actuated or pulled in one direction or the other either by an operation of the hand wheel Z² and consequent rotation of the drum Z' or through the tilting of the aeroplanes S as will be more fully described hereinafter. The hand wheel Z² or drum Z' is preferably provided with a 110 latch for maintaining the drum against rotation except when such rotation is desired. This catch may comprise any suitable device adapted for the purpose desired and has been shown as consisting of a lever Z⁷ 115 pivotally mounted on the wheel Z² and having its one free end maintained in a notch in a suitable stationary part of the ship as for instance the standard I by a spring or any other convenient means. The drum Z' 120 and wheel Z² are thus normally locked against rotation and may be released when rotation thereof is desired by simply depressing one end of the lever Z⁷ to lift its other end from its coöperating notch. The 125 wire Z is connected to weights Z⁸, Z⁹ located on opposite sides of the vessel and slidably mounted on guide bars Z¹⁰ secured to the aeroplane frames and extending inwardly toward each other from the free ends of 130

said aeroplane frames as illustrated diagrammatically in Fig. 6. The connection of the weights Z^s and Z^o to the wire Z may be made by interrupting the said wire at the proper places and connecting its ends with eyelets Z^{11} located on each weight or in any other manner to obtain an actuation of the said weights as the wire Z is moved or in other words to prevent a relative movement between said weights and said wire Z .

It is of course to be understood that the usual levers are provided for starting and stopping the engine and for operating any clutches which may be found necessary, 15 these elements having been omitted for the sake of clearness.

When it is desired to operate the vessel the engine and propeller are started in the usual way and the horizontal rudders L^s 20 titled so as to project upwardly to cause the vessel to rise. When the desired altitude has been reached the said rudders L^s are returned to their normal horizontal position in which condition the propeller O^2 will propel the vessel which may be steered to the right or left by a manipulation of the hand wheel H' and a consequent actuation of the vertical rudder D to bring about the desired change in the direction of travel. As long 25 as no disturbing air currents or other influences are encountered the vessel will travel in equilibrium, the planes S being maintained in proper position by the locked hand wheel Z^2 which prevents a rotation of the drum Z' and a consequent pull on the wire Z . In this condition the ailerons W^2 30 are fully wound on their respective rollers W or in other words in their normal position owing to the action of the springs contained in each roller which springs always exert a torsional stress tending to keep or return the said ailerons in and to this position. Should any disturbing air current 35 cause the planes S to be tilted for instance to the position shown in Fig. 2, the rings Q and Q' will travel on the rollers P relatively to the rings B and B' , the platform G and everything carried thereby including the operator's seat M and consequently the operator 40 will remain in the original position of equilibrium and will not be affected by this change in the position of said planes S . The weight of the engine N and other elements will assist to keep the said platform 45 G and with it the operator in this initial position, the said platform G being placed as low as possible in the rings B and B' to secure an extremely low center of gravity. As 50 the planes are tilted as described, the wire Z will be held against any movement owing to the fact that the hand wheel Z^2 is locked and thus prevents a rotation of the drum Z' , so that said planes will move in a circular path transverse of the machine and relatively to the wire Z and the rings B and B' .

and connected parts. This will cause a pull to be exerted on the right hand aileron W^2 which will thus be drawn downwardly along and downwardly and rearwardly inclined members of each frame X to the position 55 shown in Fig. 2, so that a considerable surface area of this aileron is exposed to the influence of the disturbing air current. The area of the plane on that side of the machine which tilts downwardly is thus augmented 60 by the said aileron and as this increased surface extends rearwardly as well as downwardly the pressure of the air current thereon will have a camming effect and will tend to lift or raise the depressed side of the aeroplane and return it to normal horizontal position. At the same time that the aileron W^2 is thus operated the left hand aeroplane in rising will cause the left hand rollers Z^4 65 to move upwardly along the wire Z and will bring the outer end of said left hand aeroplane nearer to the weight Z^s , in other words having the effect of moving said weight Z^s along its rod Z^{10} toward the said outer end of or away from the longitudinal center of the vessel. Coincidently with this operation the right hand aeroplane in descending will cause the right hand rollers Z^4 to move downwardly 70 along the wire Z and will move the outer end of the said right hand aeroplane away from the weight Z^o , in other words having the effect of moving said weight Z^o along its rod Z^{10} nearer to the longitudinal center of the vessel. The said weight Z^s will thus exert 75 a tendency to depress the left hand aeroplane and thus assist the action of the air current on the right hand aileron W^2 to return the vessel to equilibrium, while the effect of the weight Z^o will be removed from the right hand aeroplane owing to the fact 80 that its location is now nearer to the center of the vessel. In other words the effect of the weight Z^s will be increased and that of the weight Z^o will be diminished which combined with the camming action of the air pressure on the right hand aileron W^2 will 85 quickly return the planes to equilibrium. If the planes tilt in the reverse direction the left hand aileron will be operated in the same way and the action of the weights Z^s 90 and Z^o will be reversed from that just described, the operation and result being otherwise the same. It is, of course, to be understood that a manual operation of the hand wheel Z^2 will draw down one or the other aileron W^2 and shift the weights Z^s and Z^o as may be desired and that under certain conditions the automatic operation 95 above described may be augmented by a manual operation to draw the particular aileron W^2 farther down and the weights Z^s and Z^o nearer to or farther away from the center of the machine as the case may be. During all the movements and operations 100 described the rings B and B' , platform G , 105

115

120

125

130

and main frame of the machine, including the vertical and horizontal rudders D and L³ will remain unaffected and in their normal position of equilibrium so that the operator will remain upright and the vessel capable of being guided up or down or to the right and left as may be found necessary.

It is to be understood that the drums H, J are arranged within each other interiorly 10 of the drum Z' so as to all be movable one relatively to the other, the standard I forming a bearing or journal for all three of said drums. This construction is so obvious that detail illustration thereof has been considered unnecessary.

In Fig. 7 I have shown the frames α , which correspond to the frames X of the first form, extending outwardly from the outer end of each aeroplane frame and in 20 the same directions as do said aeroplane frames. In this form the aileron w^2 will be drawn downwardly toward the aeroplanes as said planes tilt in one direction or the other, the operation and effect of this form of my 25 invention being otherwise the same as the form first described.

It will be seen that in both forms of my improvement I provide effective and easily operated devices for returning the planes to 30 normal position, and a structure in which the planes are capable of a tilting movement relatively to the operator's platform which always remains in equilibrium. It is to be further understood that although I have 35 shown and described my improvements as embodied in an aeroplane of the monoplane type, I do not limit myself to this type of air ship and that my invention may be used in connection with biplanes, hydroplanes or 40 any other types of air ship to which it may be adapted. It is further to be understood that the weights Z⁸ and Z⁹ may be omitted and the ailerons W² used alone or the ailerons omitted and the weights alone.

In order to maintain the rings B and Q and B' and Q' in operative relation to each other I may provide any suitable means, as for instance rollers Q³ journaled in the bars O² and bearing against the outer surfaces of 50 the rings Q and Q' respectively as shown in Figs. 3 and 4. To add to the stability of the ship those portions of the bars A located between the rings Q and B' may be covered with a fabric A' as indicated in Fig. 3. This 55 fabric A' in addition to acting as a parachute as the vessel descends will also serve as a covering to protect the aviator, platform G and the parts carried thereby.

Various modifications may be made within 60 the scope of the claims without departing from the spirit of my invention.

I claim—

1. An air ship comprising a main frame,

aeroplanes capable of tilting transversely relatively thereto, means for augmenting the 65 effective surface area of the downwardly tilting aeroplane to cause said planes to be returned to normal position, and weights connected with said surface augmenting means and concurrently movable therewith toward and away from the center of the ship whereby the action of said augmenting means in returning the aeroplanes to normal 70 position is assisted.

2. An air ship comprising a main frame, aeroplanes capable of tilting transversely relatively thereto, means for automatically augmenting the effective surface area of the 75 downwardly tilting aeroplane to cause said planes to be returned to normal position, and weights connected with said surface augmenting means and concurrently movable therewith toward and away from the center 80 of the ship whereby the action of said augmenting means in returning the aeroplanes to normal 85 position is assisted and manually operated means for concurrently actuating said augmenting means and said weights independently of said aeroplanes.

3. An airship comprising a main frame, an operator's platform carried by said main frame, an auxiliary frame rotatably mounted in said frame, aeroplanes secured to said auxiliary frame to move therewith, and normally inactive ailerons adjacent to the outer 90 end of each aeroplane adapted to be separately brought to an operative position to 95 augment the effective surface area of one or the other of said aeroplanes and weights 100 movable toward and from the center of the ship and operatively connected with said ailerons to coöperate therewith to return the 105 aeroplane to normal position.

4. An airship comprising a main frame, an operator's platform carried by said main frame, an auxiliary frame rotatably mounted in said main frame, aeroplanes secured to 110 said auxiliary frame to move therewith, and normally inactive ailerons adjacent to the outer end of each aeroplane adapted to be 115 separately drawn to an operative position to augment the effective surface area of one or the other of said aeroplanes and weights 120 movable toward and from the center of the ship and operatively connected with said ailerons to coöperate therewith to return the aeroplane to normal position, and means for operating said ailerons and said weights.

In testimony whereof, I have hereunto set my hand in the presence of two subscribing witnesses.

MORRIS NEWGOLD.
